GAS CONTAINER FOR LABORATORY OR SIMILAR USE

Philip E. Scott, Jr., Moorestown, and Lester D. Burgess,
Cinnaminson, N.J., assignors to Lif-O-Gen, Inc., Lumberton, N.J., a corporation of Delaware

Filed Dec. 27, 1965, Ser. No. 328

Term of patent 14 years

(Cl. D16—2)

FIG.1.

FIG.3.

FIG.2.

FIG.5.

FIG.4.

FIG. 1 is a perspective view of a gas container for laboratory or similar use showing our new design;

FIG. 2 is a side view of the gas container for laboratory or similar use shown in FIG. 1;

FIG. 3 is a top plan view thereof;

FIG. 4 is a rear view thereof; and

FIG. 5 is a front view thereof.

The stippling in FIGS. 1, 2, 3 and 5 indicates color contrast.

We claim:

The ornamental design for a gas container for laboratory or similar use, substantially as shown and described.
